UNITED STATES PATENT OFFICE

163,958

AIR FILTER CLEANLINESS INDICATOR OR THE LIKE

Earl Newville, Detroit, Mich.

Application March 22, 1951, Serial No. 14,589

Term of patent 3½ years

(Cl. D52—1)

To all whom it may concern:

Be it known that I, Earl Newville, a citizen of the United States of America, residing at the city of Detroit, State of Michigan, have invented a new, original, and ornamental Design for Air Filter Cleanliness Indicator or the Like, of which the following is a specification, reference being had to the accompanying drawing, forming a part hereof.

Fig. 1 is a front elevation of an air filter cleanliness indicator showing my new design.

Fig. 2 is a side elevation of the indicator.

Fig. 3 is a sectional view of the vane element shown in Fig. 2 on the line 3—3 of Fig. 2.

I claim:

The ornamental design for an air filter cleanliness indicator or the like, as shown.

EARL NEWVILLE.
